UNITED STATES PATENT OFFICE.

JOHN L. DICKINSON, OF DETROIT, MICHIGAN, ASSIGNOR TO THE LAURENCE SMITH PAPER GOODS COMPANY, OF DETROIT, MICHIGAN, A CORPORATION OF MICHIGAN.

ENVELOPE.

Application filed February 14, 1921. Serial No. 444,887.

To all whom it may concern:

Be it known that I, JOHN L. DICKINSON, a citizen of the United States of America, residing at Detroit, in the county of Wayne 5 and State of Michigan, have invented certain new and useful Improvements in Envelopes, of which the following is a specification, reference being had therein to the accompanying drawings.

10 This invention relates to double pocket envelopes wherein means are provided for holding merchandise, correspondence or the like, in separate compartments, and to an arrangement thereof whereby a single flap 15 seals both compartments in such relation to each other as to close a fill-opening that is common to both compartments when the envelope is open.

The invention consists in the matters hereinafter set forth, and more particularly pointed out in the appended claims.

In the drawings:

Fig. 1 is a plan view of a blank that when folded, produces an envelope that is an embodiment of the invention.

Fig. 2 is a view showing the blank folded, ready for filling.

Fig. 3 is a view in perspective showing the envelope sealed.

30 As herein shown in preferred form, a substantially rectangular blank has a transverse folding line 2, with a pair of oppositely disposed side flaps 3 on one side of the folding line, that, when inturned upon the body of the sheet, overlap and may be pasted together, together with an end flap 4 that may be secured over the enfolded side flaps, either by pasting or by a string fastening means indicated at 5 on the end flap, and at 6 on the 40 outer side flap.

On the other side of the transverse fold line 2, there are a pair of oppositely disposed side flaps 7, which when inturned against the body of the blank overlap and are pasted together, while an end flap 8 is provided, that overlies and is pasted upon the superposed side flaps 7. The proximate edges 9 and 10 of the side flaps 3 and 7 are cut away, so as to form a fill-opening indicated at 11 in Fig. 50 2, which is common to both compartments.

The end fold 8 is gummed on the outer face as at 12, so that when the envelope is closed by folding on the line 2, the end flaps 8 seal upon the side flap 3. Thus one 55 pocket forms a closure for the other, or the

common fill-opening 11 is closed, when the envelope is completely sealed.

By this arrangement of parts a double envelope is obtained which provides for the retention under seal of the contents of two 60 pockets, one of which, however, being arranged to be opened through an end fold, if desired, without disturbing the matter in the first compartment which is still sealed.

What I claim as my invention is:

1. An envelope comprising a substantially rectangular sheet having a transverse folding line, a pair of side flaps on one side of said transverse folding line, inturned in overlapping relation, a corresponding end 65 flap arranged to overlie and be secured to the side flaps when the latter are superposed, a second pair of side flaps on the other side of the transverse folding line inturned and secured in overlapped relation, and an end 70 flap inturned and sealed over the latter side flaps and gummed on its outer face for attachment to the first side flaps when the blank is folded on the transverse line.

2. An envelope comprising a one piece 80 blank with a transverse folding line between the ends thereof, the margins of the blank being severed at the folding line and inturned into overlapping relation and secured by outer end flaps, one of which is gummed 85 on both sides to engage first the adjacent side flaps when the envelope is extended, and then the other flaps when the envelope is folded on the transverse line.

3. An envelope comprising a substantially 90 rectangular sheet having a transverse folding line, a pair of overlapping side flaps on one side of said transverse folding line, an end flap overlapping said side flaps, a second pair of overlapping side flaps on the other 95 side of the transverse folding line, the proximate edges of the side flaps aforesaid being cut away to provide a fill-opening, and an end flap overlapping the second pair of side flaps and secured thereto, the last mentioned 100 end flap having means adapted for engagement with the first pair of side flaps to close said fill-opening when the blank is folded on the transverse line.

4. An envelope comprising a substantially 105 rectangular sheet having a transverse folding line, a plurality of spaced overlapping side flaps upon opposite sides of said transverse folding line, the side flaps upon one side of said transverse folding line having a 110

greater length than the side flaps upon the opposite side of said transverse folding line, the proximate edges of said side flaps being cut away to provide a fill-opening, an end flap secured to the side flaps upon one side of said transverse folding line, a second end flap secured to the side flaps upon the opposite side of said transverse folding line, the second end flap being provided with means for attachment to the side flaps upon the opposite sides of said transverse folding line to close the fill-opening when the blank is folded on the transverse line.

5. An envelope comprising a sheet having a transverse folding line, a plurality of spaced overlapping side flaps upon opposite sides of said transverse folding line, the proximate edges of said flaps being cut away to provide a fill-opening, an end flap secured to the side flaps upon one side of said transverse folding line, a second end flap secured to the side flaps upon the opposite side of said transverse folding line, the second end

flap being provided with means for attachment to the side flaps upon the opposite side of said transverse folding line to close the fill-opening when the sheet is folded on the transverse line.

6. An envelope comprising a sheet having a transverse folding line, a plurality of spaced over-lapping side flaps upon opposite sides of said transverse folding line, an end flap secured to the side flaps upon one side of said transverse folding line to provide a pocket, a second end flap secured to the side flaps upon the opposite side of said transverse folding line to provide a second pocket, said sheet being provided with a fill-opening at said transverse folding line between said pockets, the second end flap being provided with means for attachment to the side flaps upon the opposite side of said transverse folding line to close the fill-opening when the sheet is folded on the transverse line.

In testimony whereof I affix my signature.

JOHN L. DICKINSON.
